UNITED STATES PATENT OFFICE.

JOHN W. PORTER, OF ST. LOUIS, MISSOURI, ASSIGNOR TO RELIANCE OIL AND GAS BURNER COMPANY, A CORPORATION OF MISSOURI.

BURNER.

1,229,517.

Specification of Letters Patent. Patented June 12, 1917.

Original application filed May 8, 1916, Serial No. 96,196. Divided and this application filed July 24, 1916. Serial No. 110,871.

To all whom it may concern:

Be it known that I, JOHN W. PORTER, a citizen of the United States, residing at the city of St. Louis, State of Missouri, have 5 invented a new and useful Burner, of which the following is a specification.

This invention relates to improvements in burners, and specifically to the improved gas burner structure disclosed in my co-pending application Serial No. 96,196, filed 10 May 8, 1916, and of which this application is a division.

An object of the invention is to provide a simple and effective gas burner including 15 means for distributing the gas and mixing it with air effectively to distribute the flame and to oxidize the gas to promote the combustible quality thereof.

Another object of the invention is to provide 20 a burner including an annular fuel supply or distributing passage, and a jet passage, with a plurality of air mixing devices disposed therebetween.

In addition to the foregoing objects additional advantages attainable from the structure including the invention will appear from the following disclosure taken in connection with the accompanying drawings, in which—

30 Figure 1 is a plan view of a combination oil and gas burner embodying the invention.

Fig. 2 is a side elevation of the burner.

Fig. 3 is a vertical section on the line 3—3 of Fig. 1.

35 As the oil burner section of the device illustrated in the drawing constitutes the subject-matter of my application above referred to, it is unnecessary to describe such part of the structure in detail. Suffice it to say that the oil burner is arranged within the gas burner, both burners being supported by a common base casting 1, and being designed to be used together or separately at the option of the user.

40 The gas burner structure includes an annular conduit 2, supported by brackets 3 extending from the base casting 1, and disposed horizontally and projecting radially therefrom. The base casting 1 is in the form 45 of a pan and the brackets 3 support the annular conduit 2 at a distance therefrom at a slight elevation from the bottom of the base

casting. A gas supply pipe 4 is formed integral with the annular conduit 2 entering the side wall thereof.

55 The annular conduit 2 at spaced intervals has extensions 5 which open into the top wall of the annular conduit 2. From the side wall of each of the extensions 5 is an angular nipple 6 which is threaded into the 60 side wall of the said extensions 3 and projects upwardly fitting into an air mixing device.

The air mixing device comprises a hemispherical hollow casting 7 having a flat 65 wall at the bottom, the upper end of the nipple 6 threading into a central orifice in the bottom thereof. Surrounding the entrance of the nipple 6 and through the bottom plate of the casting 7 is a series of openings 8 for 70 the admission of air to the interior of the casting 7. Extending upwardly from each of the air mixing devices is a straight nipple 9 threaded into the apex of the casting 7 and extending upwardly a slight distance. The 75 jet conduit 10 has a series of openings in the bottom wall thereof registering with the openings of the nipples 9, and into which the nipples 9 are threaded. The jet conduit 10, as shown, is annular in form and of a 80 diameter slightly in excess of the annular conduit 2. The nipples 6, the casting 7 and the nipples 9 extending around the conduits 2 and 10 constitute a frame work, whereby 85 the conduit 10 is supported.

In the upper wall of the conduit 10 is formed a continuous annular series of openings 11 which constitute discharge openings or jet openings from the conduit 10. The gas entering through the gas supply pipe 4 90 to the annular conduit 2 is distributed therethrough and is discharged at intervals from the conduit 2 into the nipples 6, thence into the mixing devices 7, through the nipples 9 to the jet conduit 10 from which it is discharged through the openings 11 in an even 95 and distributed flow. As there is a plurality of the mixing devices equally disposed around the conduits 2 and 10, the air and gas mixture is uniformly maintained, the 100 air passing through the openings 8 in the mixing devices, wherein it is thoroughly mixed with the incoming gas.

I am aware that modifications within

equivalent limits may be made in the structure, and I do not limit myself therefore to the exact construction shown and described, but what I claim and desire to secure by 5 Letters Patent, is:—

1. A gas burner, comprising a base casting, a supply passage disposed about said base casting, supports between the base casting and said supply passage, a jet passage 10 arranged above said supply passage, and connections between said supply passage and said jet passage including mixing devices.
2. A burner comprising a base, a series of radial brackets integrally formed with said base, a gas supply passage encompassing said base and supported by said brackets, a gas inlet pipe to said supply passage, a jet passage having a series of perforations extending radially therethrough, a plurality of 15 hollow hemispherical castings having openings in the bottom wall thereof disposed between said two passages, and passages from the first-named supply passage to said castings and from said castings to said jet passage, substantially as specified.
3. A gas burner comprising a base casting, an annular continuous tubular conduit supported by said base casting, a gas supply pipe entering said conduit, hollow extensions in the upper wall of said conduit disposed at equally spaced intervals, angular nipples connected into the side walls of said extensions, hollow mixing devices supported by said nipples, an annular tubular passage 20 above said mixing devices having discharge openings therein, and nipples connecting said last-named passage and said mixing devices, substantially as specified.
4. A gas burner, comprising a base casting, a supply conduit, connections between the supply conduit and the base casting, a jet conduit arranged above said supply conduit, said conduit having jet discharge openings therethrough, mixing devices between 25 the supply conduit and said jet conduit having air openings in the bottom wall thereof, and connections between the mixing devices.

Copies of this patent may be obtained for five cents each, by addressing the "Commissioner of Patents, Washington, D. C."

and said supply conduit and between said mixing devices and said jet conduit.

5. A burner, comprising a supply conduit, 50 a gas supply passage entering therein, extensions disposed at equal intervals from the upper wall of said conduit constituting hollow separate chambers, angular nipples connected into the side walls of said extensions, mixing devices supported by said nipples, a jet conduit and connections between said jet conduit and said mixing devices, substantially as specified.

6. A burner including a base casting, a 60 continuous conduit, brackets around said base supporting said conduit, a gas supply passage opening into said pipe, spaced chambers extending from the top wall of said pipe, angular pipe connections extending 65 from the side of said chambers, hollow chambers supported by said pipe connections, said chambers having openings in the bottom wall thereof, pipe connections extending from the top of said last-named 70 chambers, and a second continuous pipe passage supported by the last-named pipe connections, having perforations in the wall thereof constituting jet openings for discharging the gas.

7. A burner including a cylindrical base, brackets extending from the side wall thereof, an annular conduit supported at the outer ends of said brackets, a second annular conduit, a series of equally spaced mixing devices, pipe connections between said mixing devices and said first-named conduit, and pipe connections between said second-named conduit and said mixing devices, said pipe connections and mixing devices constituting 80 85 a supporting frame for said second-named pipe passage.

In witness whereof, I have signed this specification in the presence of two subscribing witnesses.

JOHN W. PORTER.
